UNITED STATES PATENT OFFICE.

EDMUND HOFFMAN, OF BROOKLYN, NEW YORK, ASSIGNOR TO AMERICAN CAN COMPANY, OF NEW YORK, N. Y., A CORPORATION OF NEW JERSEY.

DESIGN FOR A POWDER-BOX.

51,066.

Specification for Design.

Patented July 24, 1917.

Application filed February 19, 1915. Serial No. 9,446. Term of patent 7 years.

To all whom it may concern:

Be it known that I, EDMUND HOFFMAN, a citizen of the United States, residing at Brooklyn, in the county of Kings and State of New York, have invented a new, original, and ornamental Design for a Powder-Box, of which the following is a specification, reference being had to the accompanying drawing, forming a part thereof.

On the drawing—

The figure is a perspective view of the powder box embodying the said design.

The design is characterized by a wide and

flat cylindrical body and cover, and having the top flat at its outer margin from the inner part of which margin rises a gently curved and dome-shaped top formed with central perforations.

I claim:

The ornamental design for a powder box, as shown and described.

EDMUND HOFFMAN.
